UNITED STATES PATENT OFFICE.

WILBUR QUINN, OF BATTLE CREEK, MICHIGAN.

COMBINATION SHOVEL AND SCREEN.

1,409,572.

Specification of Letters Patent. Patented Mar. 14, 1922.

Application filed December 22, 1920. Serial No. 432,551.

To all whom it may concern:

Be it known that I, WILBUR QUINN, a citizen of the United States, residing at Battle Creek, in the county of Calhoun and State of Michigan, have invented certain new and useful Improvements in a Combination Shovel and Screen, of which the following description, taken in connection with the appended claims and accompanying drawings, forms a specification.

The present invention more particularly relates to shovels for the handling of coal and ashes, although other uses for the same may be resorted to.

It very often occurs that in the burning of coal more or less of the unconsumed product is wasted in the ashes, and although some people would redeem such fuel, they usually fail to do so owing to the difficulty in sepa-

rating the same from the burned-over product and the limited time generally given in attending the handling of furnace fires. The present invention has among other objects to provide a shovel and screen in such form

that they may be used co-jointly in removing the refuse from a furnace, the cinders, coal, etc., separated from the ashes and the screen removed and its contents dumped separately from the ashes in the shovel, that its contents

may be assortable, as expedient.

Another object of the invention is to so construct the parts that the shovel and screen may be used independently, whereby the parts will be simple and substantial in construction, convenient, effective for the purpose and economical to manufacture. These and other commendable features will be apparent in the subjoined description, taken in connection with the drawings, in which Figure 1 is a perspective view of my combination shovel and screen.

Fig. 2 is a detail perspective view of the shovel.

Fig. 3 is a detail perspective view of the screen.

Fig. 4 is a side view of the shovel and screen intact.

Like marks of reference refer to corresponding parts in the different views in which A represents the shovel and B, the screen.

The shovel has an elongated rectangular bottom. It is formed from suitable sheet metal open at its forward end and closed

at its rear extremity by an upright continuation of the bottom portion. 55

The sides 1 are formed from integral extensions of said bottom, and at their rear ends abut the rear end 2 of said shovel, and are held from lateral displacement by angular extensions of said end, in which position the parts are spot-welded, riveted or otherwise secured. Preferably the sides 1 taper downward to positions near the forward open end of the shovel, as shown. A 65 suitable handle, as C, is attached to the shovel by means of a curved iron reinforcing shank 4, one end of which is received within a slotted portion of the handle and secured by means of small bolts or rivets passing 70 through the parts and fixed to the shovel bottom and back by means of rivets, as 5 and 6, respectively.

The screen frame or hod is very similar in form to the shovel and is adapted to nicely sit 75 within the latter, as shown. This frame is of sheet metal and comprises two angular sides 7, an integral back end 8, and three offset inturned ledges 9 and 10, respectively. The ledges trend inwardly on a common plane 80 and support a screen D riveted or otherwise affixed thereto. At the front or open end of the screen frame a stiffening edge or lip-plate 11 is formed of a narrow strip of sheet metal bent upon itself to enclose an edge of 85 said screen and also extension ends of the two ledges 9, at which places the parts are secured by spot-welding or riveting, as likewise is the screen and lip-plate aforesaid. The screen is stiffened by means of an underlying extremity 12 of a handle member 90 13. This handle is of flattened iron and is curved to form an elongated open hand grip, the forward curved extension of which is riveted or otherwise attached to the rear 95 or closed end of the screen frame, as shown.

When the screen is in operative position with the shovel, as shown in Figs. 1 and 4, the under handle portion rests within a slot 14 or notch in the top edge of the shovel 100 back, and the lip or front end of the screen rests within the forward open end of the shovel bottom, at which point the same is held from sliding from said shovel by means of small internal side projections or retaining stops 15 attached to or extending from the shovel sides and adapted to engage the front inclinations of the screen sides above 105

the lip aforesaid, the latter of which is designed to extend below said stops and prevent the screen at this end from jarring loose or becoming disengaged until released at the 5 handle extremity.

The shovel and its screen, while primarily intended for the sifting and handling of ashes, may be used independently of each other for various other purposes, as will be 10 evident. The parts individually are simple, symmetrical, rigid, and capable of being instantly combined or separated, as expedient, and form an article admirably adapted to various general uses.

15 From the foregoing description, taken in connection with the accompanying drawings, the objects, uses and general advantages of my invention will, it is believed, be readily comprehended.

20 Having, therefore, set forth my invention, what I claim as new and desire to secure by Letters Patent, is:—

1. In an article of the class set forth, the combination with a shovel having inwardly 25 projecting stops rearward of its forward bottom portion and on its sides, and a remov-

able screen section nesting within said shovel in a rearwardly-inclined position with a lip portion adapted to rest on the forward bottom of said shovel and underneath said stops 30 with end sides of said screen abutting said stops.

2. An article of the class set forth comprising a shovel having retaining stops rearward of its forward bottom portion and on 35 its sides, and a screen having a flattened lip across its forward end and formed with a back and sides adapted to telescope within said shovel, said screen having an under supporting member extending from said lip 40 rearwardly of said back and curving to form a looped handle member secured to said back, the lip of said screen lying on the bottom of said shovel and near its front end and adapted to abut said retaining stops on said shovel, its rear end being elevated with said supporting member resting on the back of 45 said shovel.

WILBUR QUINN.
